UNITED STATES PATENT OFFICE.

ARTHUR TREVOR DAWSON AND GEORGE THOMAS BUCKHAM, OF LONDON, ENGLAND, ASSIGNEES TO VICKERS SONS & MAXIM, LIMITED, OF LONDON, ENGLAND.

FLUID RECOIL-CHECK.

SPECIFICATION forming part of Letters Patent No. 732,676, dated June 30, 1903.

Original application filed December 9, 1901, Serial No. 85,296. Divided and this application filed July 18, 1902. Serial No. 116,089. (No model.)

To all whom it may concern:

Be it known that we, ARTHUR TREVOR DAWSON, lieutenant of Royal Navy, and GEORGE THOMAS BUCKHAM, engineer, subjects of the King of Great Britain, residing at 32 Victoria street, Westminster, in the county of London, England, have invented certain new and useful Improvements in and Relating to Fluid Recoil-Checks, of which the following is a specification.

This invention relates to hydraulic buffers for absorbing the energy of recoil in quick-firing guns.

The chief object of our invention is to provide means for controlling the velocity with which the gun runs forward after recoil, said invention being applicable to that form of recoil-buffer in which the cylinder has a hollow piston-rod and a retarding-ram extending inwardly from one end of the cylinder into the said hollow piston-rod. The piston is partly withdrawn from the ram during recoil, thereby leaving within the piston-rod a space which becomes filled with liquid that must be displaced by the ram while the gun is being run forward after recoil, provision being made for the displaced liquid to be forced through a restricted passage, thus controlling the velocity with which the gun is returned to its firing position. We provide improved means for controlling the flow of the said liquid to and from the said hollow piston-rod, as will be hereinafter described, the chief feature of our invention being the formation of the ram with passages for the liquid, which passages are controlled by a valve located in the ram, which valve is kept on its seat by the action of gravity unaided by springs or the like.

In the accompanying drawings, Figure 1 is a longitudinal section of a hydraulic buffer or recoil-cylinder constructed in accordance with our invention. Fig. 2 is a transverse section taken on the line 1 1.

A is the recoil-cylinder; B, the hollow piston-rod; B', its piston; C, the ram, which projects from one end of the cylinder and enters the hollow piston-rod. A' is the key within the cylinder A, and B² the aperture in said piston, that acts in conjunction with said key

for increasing the resistance to the recoil as 50 said piston travels in the cylinder during the recoil movement of the gun.

C' is the lug or horn on the gun to which the piston-rod B is secured.

The inner end of the ram is formed with a 55 head c, in front of which a sleeve c' is screwed or otherwise secured, the diameter of said sleeve being such as to accurately fit the interior of the hollow piston-rod like a piston. The said inner end of the ram is also formed 60 with one or more passages c² leading to a space c³, wherein the gravity-seating valve C² is situated. From this space passages c⁴ c⁵ extend, the former leading to a transverse passage c⁶, communicating with the annular 65 space around the ram C between the sleeve c' and a bushing b, screwed or otherwise affixed to the piston B' and fitting around the said ram. The other passage, c⁵, leads to a longitudinal bore c⁷, extending through the 70 ram. The said bore c⁷ has one or more transverse openings c⁸, leading to the space a of the cylinder A at a point immediately in front of the piston B' when the latter is in its forward position. The opening or openings c⁸ 75 are controlled by a plug c⁹, past which the liquid has to flow from the bore c⁷ to reach the said opening or openings c⁸. By reducing the diameter of the said plug c⁹ or forming flats thereon the flow of the liquid past 80 said plug can be regulated as required.

When recoil of the gun takes place, the liquid from the space behind the piston B' flows through the passages b' in the piston, and thereby reaches the annular space within the piston-rod B, surrounding the ram C. Said liquid then flows through the passages c⁶ c⁴ and by lifting the valve c² reaches the space behind the ram through the openings c² of the ram. On the return movement of 85 the gun to the firing position the valve C² closes the passage c⁷, and the liquid within the hollow piston-rod behind the ram then flows along the passage c⁵ into the bore c⁷ and past the plug c⁹ to the opening or openings c⁸, leading to the front of the piston, thereby causing the gun to come very gently to rest in its firing position. 95

We are aware that it has before been proposed to provide a ram with a horizontal working valve controlled by spring-pressure; but valves of this kind have been found to possess the disadvantage that their action is not always certain. This disadvantage does not exist with a gravity-controlled valve. We are also aware that it has been proposed to use a gravity-controlled valve on the hollow piston-rod; but in that case there is the disadvantage that if the valve is required to be inspected it is necessary to disconnect the gun from the piston-rod and to withdraw the latter. In our case by reason of the valve being placed on the ram it is only necessary, when the valve is to be inspected, to withdraw the ram from the piston-rod without disconnecting the gun.

What we claim, and desire to secure by Letters Patent of the United States, is—

In a recoil apparatus for guns having a hollow piston-rod and a ram, the combination with the ram formed with two main passages therein both of which communicate with a recess in the ram provided with passages communicating with the hollow piston-rod

at the rearward end of the ram, one of the aforesaid main passages being comparatively short and opening laterally into a space between the ram and the hollow piston-rod and the other of said main passages being comparatively long and extending forward and opening radially into a space in front of the piston, a gravity-seating valve in the said recess normally closing the said short passage, a sleeve fixed on said ram near its inner end at a point in rear of the lateral opening of the said short passage and fitting the hollow piston-rod, a bushing in the piston fitting said ram, and an adjustable plug on the cylinder entering and controlling the forward end of the aforesaid long main passage in the ram, substantially as described.

In testimony whereof we have hereunto set our hands, in presence of two subscribing witnesses, this 7th day of July, 1902.

ARTHUR TREVOR DAWSON.
GEORGE THOMAS BUCKHAM.
